ELEVATOR SAFETY DEVICE.

1,242,394.

Specification of Letters Patent.

Patented Oct. 9, 1917.

Application filed February 14, 1914. Serial No. 818,795.

To all whom it may concern:

Be it known that I, ISAAC H. VENN, a citizen of the United States, residing in Yonkers, in the county of Westchester and 5 State of New York, have invented a new and useful Improvement in Elevator Safety Devices, of which the following is a specification.

My invention relates to safety devices for 10 elevators, and has for an object the provision of means for applying a brake to an elevator car or its counterbalance weight, or both, in case of emergency, said brake automatically effecting a retarding action 15 in accordance with the load.

A further object of the invention is the provision of an elevator safety device which may be automatically operated with varying degrees of power depending upon conditions. 20

Other objects of the invention will appear hereinafter, the novel combinations of elements being pointed out in the appended claims.

25 In the accompanying drawings, Figure 1 represents diagrammatically an elevator installation containing an embodiment of my invention; Fig. 2 is an enlarged detail view of the safety device as applied to the elevator car; Fig. 3 is a sectional end view of the safety plank; Fig. 4 is a view showing a modification.

Similar parts are designated by like reference characters in all of the figures.

35 Referring to Figs. 1, 2 and 3, an elevator car C is suspended by a cable or cables A which are associated with a driving sheave M and idler sheave I, and are secured to a counterbalance weight W. The usual guide 40 rails for the car and counterbalance weight are designated by B. Associated with the car and counterbalance weight are safety planks S, S, which not only embody novel features in themselves, but also involve a 45 novelty in the manner in which they are suspended and in which they operate. For example, the safety plank S under the car, is suspended from either end by means of cables 1, 1, which may lead up the side of 50 the car and be connected to a yoke 2 as shown. The latter is connected to a cable 3 which leads over the guide sheaves 4, 4, and is secured to the counterbalance weight W. The safety plank S under the counter- 55 weight is suspended from the cables 5, 5,

which are connected to a yoke 6. The latter is connected to a cable 7 which leads over the guide sheaves 8, 8, and is secured to the top of the car. With this arrangement of the safety planks S, S, the same normally 60 will move up and down the hatchway with the car and counterweight, while under certain conditions they may have a relative movement thereto, respectively. The cables 3 and 7 from which the car and counter- 65 weight safety planks S, S, are suspended, respectively, are adapted to be gripped by means of the clamps 9 and 10, respectively, both of which clamps are connected to a rod 11 under the control of the speed governor 70 G. The governor G may be driven from any convenient part of the elevator apparatus such as by a sprocket chain or belt 12 associated with the idler sheave I so that the governor will rotate at a speed in ac- 75 cordance with that of the elevator car. Fig. 4 illustrates a common method of driving the governor direct from the car.

The safety planks S, S, are substantially 80 similar to each other, and each comprises a pair of channels 12, 12 (see Figs. 2 and 3), to which are secured at either end a pair of massive steel blocks 13 (Fig. 3) each of which is slotted out so as to receive the guide rail web and a wedge 14. The latter 85 is provided with a head 19 which normally rests on top of the block 13 and is maintained out of contact with the rail by means of a spring 17 and stud 16, which latter is secured to the wedge and adapted to slide 90 in a groove 18 in the block 13 and one of the channels 12. To each wedge 14, 14 is pivoted a lever 20 fulcrumed at 21 to a bracket 22 carried by the safety plank channels. The pivotal connection between the 95 levers and each wedge is provided with a slight amount of side play so as to prevent cramping therebetween. The inner ends of the levers 20 on the car safety are slotted at 25 to receive a pin 26 carried by a rod 27 extending through the floor of the car and provided with a foot piece 28. A spring 29 tends to move the rod 27 and inner ends of the levers 20 upwardly and to depress the 100 wedges 14, 14. To the bottom of the car are secured a pair of plungers 31, 31, the lower ends of which are within a short distance of the plunger seats 30, 30, carried by the levers 20, 20. The plungers 31, 31, are enlarged at 32, 32, where they pass 110

through the safety plank, and these enlarged portions are embraced by channels 35, 35, which act as a means for steadyng the safety plank. Plates 34, 34, are secured 5 to the top of the safety plank and loosely surround the plungers so as to permit a relative movement of the car and safety plank within limits, but these plates will be engaged by the enlarged portions 32, 32 10 of the plungers in case the cables 1, 1, should part and thus prevent the safety plank from falling down the hatchway.

Whereas the levers 20, 20, are shown pivoted by pins 21, 21, to the center of the 15 brackets 22, I provide other holes 23, 23, in each of the brackets and levers so that the pins 21, 21, may be removed from their present location and inserted in any one of the holes 23, 23. By this arrangement I 20 provide a convenient means for varying the fulcrum of the levers 20 and thereby varying the power with which the wedges will engage the guide rails.

The operation of the safety device depends upon a relative movement between 25 the car or counterbalance weight and its respective safety plank. This relative movement may be brought about in any one of several ways, namely, by manual means under the control of the operator; by automatic speed controlled means; and automatically upon breakage of the hoisting cable or cables without regard to the speed.

In order to effect the operation of the 30 car safety device by manual means, the operator depresses the rod 27 by means of the foot pedal 28 or by hand, and in so doing the levers 20 are simultaneously rocked upon their pivots 21, 21, and the 35 wedges 14, 14, moved upwardly and into close engagement with the guide rails B. The safety plank S is now retarded in its further movement in a downward direction and the descending car carries the plungers 40 31, 31, into engagement with the levers 20, 20, and thereby forces the wedges further into engagement with the guide rails. If the pivot or fulcrum 21, 21, of the levers 20, 20, is midway between the plunger seats 45 30, 30, and the points of connection between the levers and wedges, the latter will be forced upwardly with a pressure substantially equal to the combined weight of the car and its load, whereas if the pivot or 50 fulcrum 21 of each lever 20 be located in one of the holes 23 nearer the wedge than the plunger seat 30, the upward pressure on the wedges will be greater than the combined weights of the car and its load by 55 an amount dependent upon the relative length of the lever arms. Should the pivot or fulcrum be located at one of the holes 23 nearest the plunger seat 30, the upward pressure on the wedges will be less than the 60 combined weights of the car and its load.

In any event, the retardation of the car will be proportional to the load.

The operation of the safety device by speed controlled means is effected by the governor G in the following manner. When 70 the car is operating up or down within normal speed limits, the governor G remains inactive and the cables S and 7 pass freely over their respective guide sheaves 4 and 8. If the car be descending, and for some reason 75 its speed should become excessive, the governor balls will fly outwardly and depress the governor rod 11 and thereby actuate the eccentric clamps 9 and 10. The clamp 9 will immediately grasp the cable 80 3 and retard its further movement therethrough. Now, since the cable 3 suspends the safety plank S under the car, it follows that the latter will be arrested in its downward movement, and the descending car will 85 settle upon the levers 20, 20, which will at once raise the wedges 14 into engagement with the guide rails, and the car will be gradually arrested in accordance with the load and finally stopped, the safety plank 90 being carried downwardly with the car. It will be observed that the safety device on the counterbalance weight will not be operated by the governor with a descending 95 car, since the governor clamp 10 merely places a braking action on the cable 7, and as the counterbalance weight is moving upwardly at this time there will be no relative motion between the counterweight and its corresponding safety plank.

In the event of excessive speed with an ascending car, the governor clamp 10 will restrain the cable 7 which supports the counterweight safety plank, and the latter will be retarded, whereupon the counterweight will settle upon the levers of its safety plank and the corresponding wedges will operate to retard and arrest the counterweight. If the descending car is stopped 105 by its corresponding safety device, the driving traction between the sheave M and the hoisting cable becomes destroyed and the counterweight will not be further raised even though the sheave M continue to be driven. The same thing takes place when 110 the counterweight safety operates with an ascending car. If the traction driving sheave be replaced by a winding drum and the car be arrested by its safety plank, there will be no danger of the counterweight being 115 hoisted to the top of the hatchway, since the unbalanced weight of the counterweight will be in excess of the power of the hoisting engine or motor and the latter will be stalled. The same thing will take place if 120 the car be ascending, to wit, the counterweight will be arrested by its safety plank, and the unbalanced load represented by the loaded car will stall the motor.

It will be observed that I provide a stop 125

36 in connection with the governor G, the purpose of which is to prevent the clamps 9 and 10 from positively locking the corresponding cables 3 and 7. Some arrangement of this kind is desirable since it obviates all danger of crushing the cables and subjecting them to an undue strain, while at the same time it permits the clamps to grasp their respective cables with sufficient power 10 to arrest the movement of their corresponding safety planks, and thereby enable the car or counterweight, as the case may be, to settle on the said planks and actuate the wedges. Other types of clamps may be used 15 if desired other than the eccentric type as illustrated, but I prefer to use a clamp whose power may be predetermined so as to effect a known retardation of the cables 3 and 7 of which there are many kinds, the 20 ones herein shown being merely by way of example.

As before pointed out, the safety device is arranged to be operated not only by the operator and also automatically in the event 25 of excessive speed, but also in case the hoisting cable or cables part, regardless of whether the car be in motion or not. This feature in itself is of the greatest importance since it insures that in case the hoisting 30 cable or cables part, both the car and counterweight immediately become locked to their respective guide rails, long before either the car or counterweight have had time to acquire even a moderate speed.

35 In the conventional type of elevator safety device, as soon as the hoisting cables break, the car and counterweight at once start to fall and in a very few seconds this speed becomes dangerous and far above the normal 40 running speed of the elevator. As the safety clamps are usually speed controlled the safety device does not come into effective operation until after the car has fallen a substantial distance and moreover is falling at 45 a very high rate of speed. If the cables should part while the car were near the top of the hatchway, the safety clamps would have a chance to stop the car before it reached the bottom of the well, but if the 50 cables should part with the car near the bottom of the well, the safety device would not have an opportunity materially to check the speed of the car before it struck the bottom. The counterweight in the meantime suffers 55 a free fall and in all likelihood will do great damage.

By reason of my invention I am enabled to arrest both the car and counterweight in case the hoisting cables part before either 60 the car or counterweight has had time to fall more than a very few inches at most, so that all danger of a free fall at high speed is absolutely done away with.

Referring to Fig. 1, let us suppose that 65 the car is at rest, and the hoisting cable or

cables A should part. The car and counterweight are now free to fall and will at once attempt to do so. As the counterweight moves downwardly it raises the safety plank S under the car, while at the 70 same time the car, in moving downwardly, raises the safety plank S under the counterweight, hence it will be seen that the car and its safety plank are carried in opposite directions toward each other while the 75 counterweight and its safety plank are simultaneously moving in opposite directions toward each other. By reason of this operation the wedges on both of the safety planks will almost instantly be applied and both 80 car and counterweight will be arrested before either has moved more than an inch or two at the most and consequently long before either the car or counterweight have had time to attain even a moderate speed in 85 a downward direction.

It will further be observed that the retarding power of the wedges is greater in case the hoisting cables break than would be the case if the safety device were operated 90 by hand or by the governor. In the latter case the safety plank under the car is arrested by the governor clamp, and the car settling down on the levers 20, 20, applies the wedges with a power depending upon 95 the weight of the car and its load and also upon the retardation of the safety plank induced by the governor clamp. In case the hoisting cable or cables break, the total power applied to the car safety wedges is 100 that due not only to the weight of the car and its load acting through the levers 20, 20, but also to the added power due to the upward movement of the car safety plank, which upward movement will be effected by 105 a considerable part of the weight of the counterbalance weight. To better illustrate the action of the car safety under these conditions, we may assume that the car and its load weighs 5000 lbs., while the counterweight weighs 4500 lbs. If the hoisting cable or cables should break, the car will settle on the levers 20, 20 with a pressure of 110 5000 lbs. while the counterweight is pulling up on the car safety plank with a force of 4500 115 lbs., ignoring for the time being the action of the counterweight safety. The total force exerted on the levers 20, 20 will therefore be, we may say, 5000 lbs. + 4500 lbs., or 9000 lbs. The same thing is taking place 120 in connection with the counterweight and its safety device, and the ultimate result will be that the braking power of the wedges is far in excess of what it would be in case the safety device were actuated by the gov- 125 ernor under excess speed conditions. While the action of the safety wedges under the counterweight will not permit the entire weight of the latter to act upon the safety plank under the car, and likewise, the action 130

of the safety wedges under the car will not permit the entire weight of the car and its load to be available to raise the safety plank under the counterweight, nevertheless a 5 large portion of these weights is available to effect a powerful action of both the car and counterweight wedges, and the car and counterweight will be immediately arrested.

The different degrees of power with which 10 the safety devices of the invention act according to whether the car be moving at excessive speed or whether the hoisting cables part, is a feature of the utmost value from a practical standpoint and for the following 15 reasons: In case the hoisting cables remain intact, the power necessary to stop the car and counterweight will not be greater than that required to bring the unbalanced load to rest. This case calls for a safety device 20 of moderate power. On the other hand, in case the hoisting cables part, the power of the safety devices will automatically be greatly increased so as to take care of the unbalanced car and counterweight which 25 now represent a dead load. By this arrangement the action of the safety when operated by hand or automatically by the governor will be moderate and in proportion to the load, so that the car will always come gradually and easily to a stop whatever the load 30 may be, and hence all shocks and jars to the elevator apparatus or discomfort to the passengers is avoided. When the hoisting cables part, the action of the safety device 35 in stopping the car and counterweight is so extremely rapid that there can be no possibility of the car attaining any appreciable speed and hence there can be no shock or jar, notwithstanding the great power of 40 the safety at this time.

Whereas the parting of the hoisting cables of any elevator installation is but a very remote possibility when the apparatus is properly inspected from time to time, the 45 likelihood of the car attaining an excessive speed from some disarrangement of its hoisting machinery, or in the case of an electric elevator, from some defective electric switch or false operation in the controlling circuits, 50 or otherwise, is much more likely to occur and frequently does. In the generally accepted type of elevator safety device, the braking or retarding action of the same must be such that the car will be arrested 55 smoothly and without shock or jar when the car contains its maximum load. If the car is but lightly loaded, and the safety device operates, it is readily perceived that the braking action of the safety device being invariably the same is much too powerful, and the car will suddenly come to rest with a 60 violent shock. Should the safety device be set and adjusted so as properly to stop a lightly loaded car, a heavily loaded car will 65 not be stopped at all, but will slide on down

the hatchway with little checking of speed until it strikes the bottom of the shaft with great force, which of course, is most likely to result in serious damage both to the car and its load of passengers.

By reason of my invention I am enabled to apply a braking action to either the car, counterweight, or both, which shall automatically be in proportion to the load. If the load be light, the braking action will be 70 correspondingly gentle; if the load be heavy, the braking action will be correspondingly powerful. In each case the retarding action of the safety device is automatically increased or decreased in proportion as the 75 load increases or decreases, the arresting of the car being effected gradually and gently without any possibility of shock or jar and regardless of load conditions. Furthermore 80 since the retarding power of my safety device is proportional to the load, it follows that for a given speed the elevator car may 85 always be stopped within a predetermined distance regardless of the load.

The pitch of the wedges 14, should preferably be such that under no circumstances can the wedges be immovably jammed between the guide rails and the steel blocks 13. The relative length of the arms of the levers 20 as determined by the position of 90 the adjustable fulcrum 21 with respect to the plunger seat 30 and pivotal connection between the lever and the wedge, may best be determined by experiment so that the upward pressure on the wedges will not be 95 excessive. If desired, the pitch of the wedges and the length of the lever arms may be so proportioned that the resultant brake action will be just sufficient to bring the car and counterweight to a very slow speed so that 100 the car will not be brought to rest, but may slowly slide down the guide rails and gently come to rest at the bottom of the hatchway. This feature is not found in elevator safety devices in present day use and is of great 105 practical value. For example suppose an elevator be equipped with the usual safety device and a fire should break out in a building. The elevator, under these conditions would be operated as rapidly as possible and 110 at the same time would in all likelihood be heavily overloaded on each downward trip. This condition is most favorable for excessive speed, and this speed might easily rise above that at which the speed governor is 115 set to operate. Under these conditions the safety device will act and the car will be locked in the hatchway against movement, and the entire load of passengers consumed without any possibility of saving themselves 120 or of receiving aid from an outside source. By reason of my invention the safety devices could be so adjusted that the elevator car would not be brought to rest at an intermediate point in the hatchway, but would 125 130

be gradually retarded to a slow speed regardless of the load and then permitted gently to slide down to the basement landing, where it would bottom without damage 5 to itself or its live load.

It will be observed that the wedges will always operate simultaneously due to the slot and pin connection between the levers 20, 20, so that the brake action on each side 10 of the car or counterweight is the same and comes into effect at the same time, so that there will never be a tendency for the car or counterweight to cant.

It may further be observed that the safety 15 device is self resetting. For example: If the car be arrested by the manual operation of the safety device or automatically due to excessive speed in a downward direction, the hoisting motor may be reversed and the 20 car lifted out of engagement with the levers of its safety plank. The spring 29 will in all probability retract the wedges to their normal inactive position, but if this spring should lack the necessary power, a slight 25 upward pull on the pedal 28 will effect the desired result. In like manner, if the safety device on the counterweight be operated with an ascending car, and the hoisting motor be reversed, the spring associated with 30 the counterweight safety levers 20, 20 will assist in returning the wedges to normal position out of engagement with the guide rails.

I desire not to be limited to the precise 35 construction and arrangement of parts herein disclosed, since it is obvious that various changes and modifications could readily be made by one skilled in the art without departing from the spirit and scope of the 40 invention.

What I claim is:—

1. The combination with a car and counterweight and their respective guide rails, of a cable connecting the car and counterweight, a safety device under the car and counterweight, separate cables connected to the car and to the counterweight, respectively, for suspending each safety device independent of the first named cable connecting the car and counterweight and of each other, and means for effecting the operation of said safety devices upon an abnormal relative bodily movement between the car and counterweight.

55 2. The combination with a car and counterweight and their respective guide rails, of a hoisting cable connecting the car and counterweight, a safety device under the car and counterweight, respectively, means for sus-

pending said safety devices independently 60 of said hoisting cable and of each other, and means operative upon breakage of the hoisting cable for effecting a movement toward each other of the car and its safety device and the counterweight and its safety device 65 to effect the sudden actuation of both of said safety devices.

3. The combination with a car and counterweight and their respective guide rails, of a hoisting cable connecting the car and counterweight, a safety device under the car and counterweight respectively, means for suspending said safety devices independently 70 of said hoisting cable and of each other, and automatic means operative upon excessive 75 car speed for effecting a movement toward each other of the car and its safety device and the counterweight and its safety device to effect the actuation of said safety devices.

4. The combination with a car and counterweight, of safety devices carried by the said car and counterweight, speed controlled means for effecting the operation of the safeties, a connection between the safety on the counterweight and the car, and an independent connection between the safety in the car and the counterweight, the car increasing the application of the safety of the counterweight through said connection, and the counterweight increasing the application of 90 the safety to the car through the other connection.

5. The combination with a car and counterweight, of a cable connecting the car and counterweight, a safety for the counterweight, a separate safety for the car, a cable connecting the car with the safety on the counterweight, another cable connecting the safety on the car to the counterweight, these cables being independent of the first named 95 cable, and adapted to apply the said safeties simultaneously to the car and counterweight.

6. The combination with a car and counterweight, of a cable connecting the car and counterweight, safety devices for the car and counterweight, a cable connecting the counterweight safety and car direct, another cable connecting the car safety and counterweight direct, and speed controlled means for operating one or the other of said safeties in both directions of travel of the car.

In testimony whereof, I have signed my name to this specification in the presence of two subscribing witnesses.

ISAAC H. VENN.
